UNITED STATES PATENT OFFICE.

GEORGE B. DURKEE, OF CHICAGO, ILLINOIS.

PIANO.

SPECIFICATION forming part of Letters Patent No. 660,183, dated October 23, 1900.

Application filed January 19, 1900. Serial No. 1,974. (No model.)

To all whom it may concern:

Be it known that I, GEORGE B. DURKEE, a citizen of the United States, residing in Chicago, in the county of Cook and State of Illinois, have invented a new and useful Improvement 5 in Pianos, of which the following is a specification.

My invention relates to improvements in pianos.

10 Heretofore in the construction of pianos the strings have been customarily strung on or over a heavy strong cast-iron or other metal plate weighing from one hundred and fifty to two hundred and fifty pounds or more and to 15 which the opposite ends of the strings are connected either directly or through the customary wooden pin-block which ordinarily abuts against one edge of the metal plate, this strong heavy metal plate being calculated 20 to resist and serving to resist the enormous aggregate strain of the multitude of strings, and the connection between the strings and the sounding-board (through which all the tone is ultimately developed and which here- 25 tofore has ordinarily been made quite thin, generally about three-eighths of an inch in thickness) has been simply through the bridge or bridges connected to the sounding-board and over which the strings pass and against 30 which they exert, at least when the piano is new, a light pressure at right angles to the plane of the sounding-board and to the direction of the strain of the strings, the strings and sounding-board being substantially par- 35 allel to each other. In this old construction where the thin sounding-board is subjected to a slight pressure from the strings in a direction at right angles to its plane, owing to the nature of the pressure and the fact that 40 it is always in one direction, the sounding-board frequently finally gives up under this pressure in one direction and the rapid vibrations of the strings until there is little or no pressure of any kind of the strings upon 45 the sounding-board, which condition results in a very thin unsatisfactory sound, and for the same reason pianos of this old construc- 50 tion instead of improving with age and use speedily deteriorate and are comparatively short-lived, especially when subjected to anything like constant use.

The object of my invention is to provide a

piano of a simple, efficient, and durable construction which will produce a more mellow tone and superior results to those heretofore 55 in use and which at the same time will tend to improve in quality and tone from age and use instead of deteriorating and in which also the cost of construction is materially lessened.

60 A further object is to lessen the weight of the piano and to greatly facilitate its portability.

These important objects or results, I have discovered, may be accomplished (and I have 65 so demonstrated by experiment) by combining with a thick sounding-board strings strung directly on the board—that is to say, so that the entire tension and strain of the strings is exerted directly upon the sounding-board it- 70 self, so that the sounding-board, as well as the strings, is kept constantly under tension or strain. By this direct combination of the strings with the sounding-board I find by actual experiment and demonstration that 75 the tone of the piano is greatly improved in volume and quality over that produced by the old construction and that a much better and mellower effect is also produced, while at the same time, remarkable as it may seem, 80 the instrument will stand or remain much more perfectly in tune and for a much greater length of time than is the case with the old construction of pianos, and my experiments also tend to indicate that my new construc- 85 tion of piano does and will grow better and better in tone and quality with age instead of tending to deteriorate.

In practicing my invention I employ a much thicker sounding-board and provide it with 90 larger ribs than have heretofore been considered possible in piano construction to enable it to properly withstand the enormous combined tension of the strings, and I combine all the strings with the sounding-board 95 itself through the pin-block, which abuts against one edge of the board and the bridge or bridges, which are connected directly to the board at the opposite ends of the strings, so that the entire strain and tension of the 100 strings is brought to bear directly on the sounding-board itself, where all tone-vibrations are finally developed. My sounding-board is thus itself maintained under the enor-

mous aggregate compression tension of the numerous strings, thus giving it a wonderful tonal capacity.

In practicing my invention the sounding-board is preferably made from five-eighths of an inch to one inch in thickness, and the strengthening-ribs with which it is provided at intervals I ordinarily make from five-eighths of an inch to one inch or more in thickness.

10 In the accompanying drawings, which form a part of this specification, Figure 1 is a plan view of a piano sounding-board and strings embodying my invention. Fig. 2 is a vertical section on the line $x-x$ of Fig. 1. Figs. 3, 15 4, 5, and 6 are enlarged detail sections on lines 3 3, 4 4, 5 5, and 6 6 of Fig. 1, respectively; and Fig. 7 is an enlarged detail plan view of a portion of the spring-bridge which is secured to the sounding-board.

20 In the drawings, A represents the frame of the piano or a portion thereof.

B is a thick sounding-board, the same being preferably about three-fourths of an inch in thickness and provided with a series of 25 heavy strengthening-ribs b on its back side and extending in a diagonal direction across the board and parallel to each other. The sounding-board is also provided with transverse ribs b', extending, preferably, at right angles to the ribs b. The ribs b are preferably about an inch thick and about the same in width.

C is the wooden pin-block, the same being of any usual or customary construction. One 35 edge of the sounding-board abuts directly against this pin-block.

D D' D² are the strings, the same being all connected at one end to the pin-block C by the customary wrist-pins C'.

40 F and F' are the bridges. The main or central bridge F extends centrally and diagonally across the sounding-board and transversely to the ribs b and is preferably curved about as illustrated in the drawings. The

45 lower bridge F', to which the spring-bridge F² is attached, extends across the corner of the board and is preferably curved about as illustrated in the drawings. The bridges F F' are securely glued to the sounding-board, and the 50 spring-bridge F² and bridge F' are in addition secured together and to the sounding-board by carriage-bolts f and wood-screws f', which are set at an angle and furnished with tapering washers f², the screws and bolts being in-

55 clinched in the direction of the strain of the strings on the spring-bridge, so that the tension of the strings will tend to compress the bridges and sounding-board more tightly together instead of to pull them apart, as would

60 be the case if the screws and bolts were inclined in the opposite direction or set at right angles to the plane of the sounding-board. I also employ blind dowel-pins f³ to give additional security to these parts.

65 The covered strings D, which constitute the overstrung portion of the instrument, are connected at one end, as before stated, to the

pin-block and at their opposite eye ends to the spring-bridge F², which is provided with slots f⁴ to receive the twisted eye ends d of the 70 strings, through which eye ends the holding-pins d' are inserted, as shown, for example, in Figs. 1, 6, and 7.

The plain steel strings D', covering the middle section of the instrument, are passed over 75 the bridge F and through small holes b² in the sounding-board B and through a hard-wood strip G, glued to the back side of the sounding-board, and around the metal pin g and back through a contiguous hole in the sounding-board, thus making two strings. In case 80 a single string is required an eye is twisted on its end through which the pin is inserted, the single string passing through a single hole at the back of the bridge, as before described. As shown in Fig. 4, the string D' is passed around under the head of an inclined wood-screw f', by which the bridge F is secured to the sounding-board, such wood-screws being inserted at the intersection of the 90 bridge F with the ribs b. This method of securing the end of the string may be employed at any point on the bridge, but is particularly applicable at the points where the ribs b intersect the bridge and renders it unnecessary to 95 pass the strings through the sounding-board and rib.

The strings D² of the upper register I prefer to pass over the bridge F, as illustrated in Fig. 3, and secure their ends to the sounding-board by inclined wood-screws h h, which pass through hard-wood strips H H' on opposite sides of the sounding-board and which extend parallel to the bridge F. These hard-wood strips H H', which run parallel with the 105 bridge F, form additional strengthening-ribs for the sounding-board and support this portion of the board, where the strings are short, numerous, and close together, in such manner as to assist greatly in bringing out the higher 110 tones of the instrument.

In Fig. 1 of the drawings I have, for sake of clearness, omitted all the strings of each set D, D', and D² except a few of the marginal ones of each set.

115 In Fig. 2 of the drawings I have shown a hard-wood strip K, which, if preferred, may be placed on the opposite side of the sounding-board from the spring-bridge F² throughout a portion or a whole of the length of the 120 spring-bridge.

I find in constructing a piano sounding-board in this way and combining the strings therewith in this manner that the downward pressure of the strings upon the board immediately in front of the bridge is counteracted or counterbalanced by an upward pressure directly behind said bridge, which serves to keep the sounding-board practically in its original position, whereas in the old construction, where the strings were hitched to a metal plate or frame, distinct and separate from the sounding-board, and allowed to produce a pressure in one direction only on the sound-

ing-board, which was made thin, the sounding-board would sooner or later give way slightly under the pressure, and thus leave the strings and sounding-board practically 5 separate from and uncombined with each other and resulting in a very unsatisfactory and insufficient tone.

As will be readily understood from Figs. 2, 10 5, and 6, the component of force or pressure of the strings toward and upon the sounding-board at and through the bridge is counteracted or counterbalanced by the component of force or pressure in the opposite direction of the strings upon the board at the point 15 back of the bridge where the strings are attached to the board, as action and reaction are of course equal and as the strings are strung upon the sounding-board itself.

In my invention, as my thick heavily-ribbed 20 sounding-board is combined with strings strung directly thereon and exerting their tension on the board in the direction of its plane, the sounding-board itself, as well as the strings, is maintained under constant tension 25 or strain and is peculiarly adapted to give out full, mellow, and resonant tones in great volume and with peculiar sweetness and perfection, and, strange as it may seem, I have found by extensive experiments that my thick 30 heavily-ribbed sounding-board, combined with strings strung directly upon it or so as to exert their tension directly upon it, is not only capable of producing the most delicate tones, as well as much greater volume and 35 perfection in quality, but it also successfully withstands the enormous aggregate strain and tension of the multitude of strings without giving way or getting out of shape, and that the instrument is also much less liable to get 40 out of tune than in pianos of the old construction. My new piano is also much less in weight, as I entirely dispense with the heavy cast-iron or metal plate heretofore generally used.

45 In pianos constructed according to my invention, wherein one end of the strings is secured to bridges attached to one side or face of the board, the anchorage of one end of the strings is on the vibratory board itself, and 50 the strings are thus all free to vibrate and for this reason produce much superior tones to strings which simply pass over the bridge and are anchored or connected to a rigid cast-iron plate.

55 In the drawings I have for convenience illustrated my invention as applied to an upright piano; but it will be understood by those skilled in the art that it is also applicable to grand pianos.

60 I claim—

1. A piano having no string-frame or metal plate to resist the tension of the strings, and comprising in combination a thick sounding-board, strings strung on the board itself on 65 one side thereof and exerting their tension or strain thereon in the direction of its plane, substantially as specified.

2. A piano having no string-frame or metal plate to resist the tension of the strings, and comprising in combination a piano pin-block, 70 a thick sounding-board abutting at one edge against the pin-block, and provided with bridges, and strings secured at one end to the pin-block and at their other ends to the bridges on the sounding-board, said strings 75 exerting their strain and tension directly on the sounding-board in the direction of its plane, substantially as specified.

3. A piano having no string-frame or metal plate to resist the tension of the strings, and 80 comprising in combination a thick, heavily-ribbed, sounding-board, strings strung directly upon the board itself and exerting their tension thereon in the direction of its plane, one part or series of said strings extending 85 across the board at an angle to another part or series thereof, substantially as specified.

4. In a piano the combination with a thick sounding-board having parallel ribs extending diagonally across the board, of a series of 90 strings D strung across the board at an angle to said ribs, and a series of strings D' D² strung across the board at an angle to said strings D, all of said strings exerting their strain or tension upon the board itself, sub- 95 stantially as specified.

5. The combination with a pin-block, of a thick, heavily-ribbed sounding-board abutting at one edge against the pin-block, and provided with bridges F, F', and spring-bridge F², of a series of strings D secured at 100 one end to the pin-block and at the other end to said spring-bridge, and a series of strings D' secured at one end to the pin-block and at the other to said bridge F, and a series of 105 strings D² secured at one end to the pin-block extending over said bridge F, and secured at their opposite ends to strips H H' secured to the sounding-board, substantially as specified.

6. The combination with a pin-block, of a 110 thick, heavily-ribbed sounding-board abutting at one edge against the pin-block, and provided with bridges F, F', and spring-bridge F², of a series of strings D secured at one end to the pin-block and at the other to said spring-bridge, and a series of strings D' secured at 115 one end to the pin-block and at the other to said bridge F, and a series of strings D² secured at one end to the pin-block extending over said bridge F, and secured at their opposite ends to strips H H' secured to the sounding-board, said strings D' passing through 120 holes in the sounding-board, substantially as specified.

7. In a piano, the combination with a thick, 125 heavily-ribbed sounding-board, of a pin-block abutting against the sounding-board at one edge, a central bridge F, an outer bridge F' having spring-bridge F² secured thereto by inclined bolts or screws, and a series of strings 130 D secured at one end to the pin-blocks passing over the central bridge F, and secured at their opposite ends to said spring-bridge, substantially as specified.

8. In a piano, the combination with the pin-block, of a thick, heavily-ribbed sounding-board, a bridge F secured to the sounding-board, and strings D' secured at one end to the pin-block and at their opposite ends passing over said bridge and through holes in the sounding-board, and provided with eyes, and pins passing through the eyes, substantially as specified.
9. A piano having no string-frame or metal plate to resist the tension of the strings, and comprising in combination a piano pin-block, a thick, heavily-ribbed, sounding-board under the compression strain in the direction of its plane of the tension of its strings, a bridge F secured thereto, and strings D², secured at one end to the pin-block and at their other ends passing over said bridge and secured to
- wood strips H H' on opposite sides of the sounding-board by screws passing through said strips and the sounding-board, substantially as specified.
10. A piano having no string-frame or metal plate to resist the tension of the strings, and comprising in combination the strings, a sounding-board under the compression strain of the tension of the strings in the direction of the plane of the board, the strings being in different series extending across the board at an angle to each other, substantially as specified.
